UNITED STATES PATENT OFFICE.

ROGER W. PERRIN, OF NEW YORK, N. Y., ASSIGNOR TO THEATRE VENDING MACHINE CORPORATION, OF NEW YORK, N. Y., A CORPORATION OF NEW YORK.

VENDING-MACHINE.

1,246,316.

Specification of Letters Patent. Patented Nov. 13, 1917.

Application filed November 2, 1915. Serial No. 59,168.

To all whom it may concern:

Be it known that I, ROGER W. PERRIN, a citizen of the United States, residing in New York city, county of New York, and State 5 of New York, have invented new and useful Improvements in Vending-Machines, of which the following is a specification.

The invention is an improvement in vending machines of the class that are attached 10 to the backs of theater chairs, and the object is to provide an exceedingly simple construction of the case and vending parts and to cause the deliveries to be made wholly by the agency of the deposited coin.

15 In the accompanying drawings illustrating the invention:

Figure 1 is a front elevation of the machine with portions broken away and in section;

20 Fig. 2 is a side elevation similarly broken away;

Fig. 3 is a vertical section on the line 3—3 of Fig. 4;

Fig. 4 is a central vertical section;

25 Fig. 5 is a horizontal section on the line 5—5 of Fig. 1;

Fig. 6 is an inside perspective view of the inner shell;

30 Fig. 7 is an inside perspective view of the outer shell;

Fig. 8 is an elevation of the inner face of the back plate before its bottom has been curled up to form the delivery receptacle;

35 Fig. 9 is an enlarged fragmentary sectional view corresponding to Fig. 4 and showing the escapement member in a different condition;

Fig. 10 is a fragmentary horizontal section taken in the plane of the hinge of the 40 trap door; and

Fig. 11 is a vertical transverse section through the hinge.

The case is of a generally flat rectangular form and comprises as its primary supporting member a back plate 1 having screw bosses 2 by which it is united to and spaced from the chair back 3 or other part to which it is attached. The lower portion of this plate is curled up forwardly to form an 45 open-end delivery receptacle 4, having a front sight opening 5. The back plate is also provided with two sets of vertical slots 6 and 7 adjacent its side edges, and a horizontal slot 8 near the top.

55 An inner shell 9 is formed from a plate

bent to present a front wall 10 and side walls 11, the latter having hooked lugs 12 on their rear edges, to take into the inner slots 6 in the back plate. This shell cooperates with the back plate to form an article magazine 13 adapted to hold a pile or vertical series of substantially cylindrical articles 14. The inner shell is without a top or bottom wall, the top and bottom of the magazine being closed as hereinafter described.

An outer shell 15, somewhat wider and higher than the inner shell, is formed with a front wall 16, side walls 17, and a top wall 18, its side walls having hooked lugs 19 to 60 take into the slots 7. These lugs may face upward, as shown, or downward like the lugs 12, as may be preferred. A lock 20 is secured to the underside of the top wall 18, with its barrel in an opening 21 therein, and its bolt 22 in position to enter the slot 8 and thereby prevent vertical movement of the shell when the latter has been raised upward to cause its hooks to interlock with the back plate. In this condition it is impossible to 65 remove the outer shell, which in turn protects the inner shell.

The front walls 10 and 16 are separated by a narrow space or compartment 23 which serves for the reception of the coins. The 70 top of this coin space, as well as the top of the magazine are covered by the top wall 18 of the outer shell. The bottom of the coin space is closed by a flange 24 on the lower end of the front wall 10 of the inner shell; and the bottom of the magazine is closed against entrance by a trap door 25, hinged at 26 and normally pressed upward by a spring 27 against a stop flange 28 struck up from the back plate 1. The said 75 spring may be coiled about the hinge pintle 29 and housed within a tube 30, as shown in Figs. 10 and 11. When the outer shell is removed both the magazine and the coin receptacle are accessible.

In the lower part of the magazine, behind the front wall thereof, is an escapement member or cradle 31, having curved working portions 32, the extremities of which represent upper and lower pallets. The said cradle has journal ends 33 which find bearings in openings in the side walls 11 of the inner shell, and a rearward projection 34 passing through and movable up and down in an opening 35 in the front 80

100

105

110

wall 10. The cradle is normally disposed with its upper pallet portions in supporting relation beneath the lowermost article in the magazine, and is adapted to be tilted 5 upward from this position by the impulse delivered by a coin to the actuating element 34. When this happens the bottom article descends, and as it does so it encounters the lower pallet portions of the escapement 10 member or cradle and rocks the latter back into holding relation to the article next above. The extent of movement of the cradle in either direction may be appropriately limited by the contact of the projection 34 with the top and bottom of the opening 35. The weight of the article delivered is sufficient to open the trap door, from which it falls into the trough 4.

The coin entrance 36 is through the upper portion of one of the side walls 17 of the outer shell, and admits the coin to a coin chute 37 ranging downward in the coin space 23. The upper section 38 of this chute may be inclined only slightly from the horizontal, and its remaining portion may be extended downward in a curve more or less as shown. Adjacent the junction of the two portions of the chute is a magnet 39, below which is an opening 40 through which iron 30 slugs are diverted by the magnet. Below the said opening a ledge 41 struck up from the front wall 10 of the inner shell serves to keep false tokens from dropping into the space below reserved for proper coins. The 35 discharge end of the coin chute, it will be understood, is to be appropriately arranged so that the emerging coin of proper size will act upon the projector 34 to displace the escapement member.

40 The side wall 17 having the coin entrance is spaced from the corresponding inner side wall 11, the space between these walls constituting a narrow well 42 wherein is guided a vertically movable shutter 43. The latter 45 is connected by a cord 44, passing over a notch 45 in the top of the side wall 11, with a ball follower 46, which rests on top of the series of articles in the magazine. As the follower descends with the diminishing 50 pile of articles the shutter is pulled upward, until when the last article is sold it blanks the coin entrance and prevents the deposit of further coins. This coin shutter since it moves concurrently and proportionally 55 with the follower also serves to indicate to a person refilling the machine the approximate number of articles remaining in the article magazine.

The operation of the parts has been explained with the description of structure. It will be understood that numerous changes in form, proportion, construction and relation are permissible.

What is claimed as new is:

65 1. A casing for a vending machine, com-

prising in combination, a supporting back plate, inner and outer shells hooked into said back plate with their front walls separated from each other by a narrow space for the reception of the coins, the inner shell 70 and the back plate together forming a magazine adapted to receive a pile of articles, and a lock for preventing vertical movement of the outer shell on the back plate.

2. A casing for a vending machine, comprising, in combination, a supporting back plate, an inner shell open at top and bottom and having a front wall and side walls provided with hooked lugs engaging slots in the back plate, an outer shell having 80 a front and a top wall and side walls also provided with hooked lugs engaging slots in the back plate, said front walls being separated by a narrow space, a coin chute carried by the front wall of the inner shell, 85 the inner shell and the back wall forming the article magazine adapted to receive a pile of substantially cylindrical articles, and a lock for preventing vertical movement of the outer shell on the back plate. 90

3. A flat box theater chair vending machine, comprising a supporting back plate, an inner shell detachably mounted on the back plate and therewith constituting an open top magazine adapted to receive a pile of substantially cylindrical articles, a removable outer shell having a top wall covering the top of the magazine and a front wall separated from the front of the inner shell by a narrow coin space having means for the reception of the coins and adapted to form a storage receptacle therefor. 100

4. A casing for a vending machine comprising, in combination, a supporting back plate, an inner shell engaged by the back 105 plate and adapted to be detached therefrom, an outer shell engaged into the back plate, the chamber defined by the walls of the inner shell and the back plate forming an article magazine, the space between the inner and outer shells being adapted to form 110 a coin storage compartment, and a delivery shelf formed by an extension of the lower end of the supporting plate.

5. A flat box theater chair vending machine, comprising a supporting back plate, an inner shell detachably mounted on the back plate and therewith constituting an open top magazine, a removable outer shell having a top wall covering the top of said 115 magazine and a front wall separated from the front of the inner shell by a narrow coin space having means for the reception of the coins, and a flange on the front of the inner shell closing said coin space at the bottom. 120

6. A flat box theater chair vending machine, comprising a supporting back plate, an inner shell mounted on the back plate and therewith constituting an open top magazine, a removable outer shell having a 130

- top wall covering the top of said magazine and a front wall separated from the front of the inner shell by a narrow coin space, a coin chute carried by the front wall of 5 the inner shell having an exit for improper tokens, and a ledge on the front of the inner shell below said exit and above the discharge end of the chute to keep such tokens separate from the coins below.
- 10 7. In a vending machine, the combination of a back plate, an inner shell mounted on the back plate and therewith forming an article magazine, an outer shell having its front wall separated from the front of the 15 inner shell by a coin space and one of its side walls separated from the corresponding side wall of the inner shell by a well, a coin chute in the coin space, a coin entrance through the said side wall of the outer 20 shell, a shutter vertically movable in and guided by the walls of said well to close said entrance, a follower adapted to rest on top of a pile of articles in the inner shell, and a flexible connection between said follower and 25 shutter.
8. In a vending machine, the combination of a magazine, a coin entrance, a follower adapted to rest on the pile of articles in the magazine, a vertically movable shutter to close the said entrance when the magazine is empty, a flexible connection intermediate the follower and the shutter, said connection being adapted to concurrently and proportionally raise the shutter on the 30 descent of articles in the magazine whereby the shutter acts as an indicator to show the number of articles remaining in the magazine.
- 35 9. In a vending machine, in combination, a supporting back plate, a detachable inner shell coöperating with said plate to form an article magazine, a detachable outer shell having its front wall spaced from the front of the inner shell by a narrow coin space 40 having means for the reception of coins and adapted to form a storage receptacle therefor and means to prevent the unauthorized detachment of the outer shell and to thereby prevent unauthorized access to the inner 45 shell.
- 50 10. In a vending machine, in combination, a supporting back plate, a detachable inner shell open at its bottom and coöperating with the back plate to form an article magazine, a detachable outer shell open at its bottom and coöperating with the inner shell to form a storage receptacle for coins therebetween, and an article delivery shelf 55 projecting downwardly from the supporting back plate and extending forwardly under the open lower ends of the inner and outer shells.
- 60 11. In a vending machine, in combination, a supporting back plate, a detachable inner shell open at its bottom and coöper- ating with the back plate to form an article magazine, a detachable outer shell open at its bottom and with the inner shell defining a storage receptacle for coins, an article delivery shelf projecting downwardly from the back plate and extending forwardly under the lower open ends of the inner and outer shells and a hinged trap door to prevent access to the interior of the inner shell through the downwardly open end thereof. 75
12. In a vending machine, in combination, a supporting back plate, an inner shell mounted on the back plate and coöperating therewith to form an article magazine, a removable outer shell having side, top and front walls covering the said inner shell and said front wall being separated from the front of the inner shell by a narrow coin space, a coin chute in said space and carried by one of the said walls, said chute having 80 an exit for improper tokens and means for diverting the improper tokens therethrough, and a ledge adapted to keep the said improper tokens from contacting with an operating means located adjacent the lower 85 end of the coin chute.
13. In a vending machine, in combination, an article magazine having side walls and a front wall, an escapement member pivoted in the side walls and adjacent the 90 front wall and having a plurality of upper pallet portions spaced apart from each other and a plurality of lower pallet portions, the said upper pallets normally abutting against the lowermost articles in the magazine and thereby retaining the said articles therein, a projecting post on the back of the escapement member projecting through a slot in the front magazine wall, a coin chute carried by said front wall for conducting a 95 coin into engagement with the said post whereby the impact of the coin therewith swings the upper pallets rearward and the lower pallets forward into the path of the descending article, the said escapement 100 member being adapted to be rocked by the weight of the descending article to swing the upper pallets away from the magazine wall and arrest the next descending article. 105
14. In a vending machine, in combination, an article magazine, an article retaining cradle pivoted adjacent one wall of the magazine, a post projecting from the said cradle, a coin chute having a curved lower end and adapted to direct coins of a proper size down the chute with a rolling movement to impact the edge of the coin against the post and rock the cradle, said coin chute being so spaced from the post that coins of small diameter will roll down the chute and 110 be discharged therefrom without impacting with the said post.
15. In a vending machine, in combination, an article magazine, an article retaining cradle pivoted therein, a post projecting 115
- 120
- 125
- 130

- from the said cradle, a coin chute having a curved lower end, and adapted to direct coins of proper size down the chute with a rolling movement to impact the edge of the
5 coin against the post and rock the cradle, said coin chute being so spaced from the post that coins of small diameter will roll down the chute and be discharged therefrom without impacting against the post,
10 and slug diverting means in the said chute for diverting slugs therefrom.
16. In a vending machine, the combination, of an article magazine, a cradle in said magazine having upper and lower pallets
15 extending therefrom, the upper of which is adapted to support the lowermost article in the magazine, a pivot mounting for the said cradle said pivot being located intermediate the pallets, a projection from said cradle
20 extending without the magazine, a coin chute carried by the magazine to direct coins against said projection, means for diverting magnetizable slugs from the said coin chute, means for preventing the descending slugs from impacting with the aforesaid projection, the said lower pallets on the cradle being adapted to be cammed rearward by the weight of an article being delivered and to thereby swing the upper
25 pallets forward to arrest the next descending article, said upper pallets being adapted to be swung forward by the impact of a coin with the projection from the cradle whereby an article is delivered.
- 30 17. In a vending machine, in combination, an article magazine having side walls and a front wall, a cradle pivoted in the side walls of the article magazine and having upper and lower article engaging portions above and below the pivotal support, a post integral with the cradle and projecting therefrom through an aperture in the front wall of the article magazine, a coin chute adapted to direct a coin in such a
35 manner as to move the post and thereby rock the cradle by the gravity of the descending coin, said cradle being adapted to

thereafter rock in the opposite direction thereby delivering one article and arresting the next descending article in the article
50 magazine.

18. In a vending machine, in combination, a back plate, an inner shell coöperating therewith and adapted to form a relatively narrow article magazine, an outer shell inclosing said inner shell and separated from the front wall thereof by a relatively narrow space, a cradle pivoted in the side walls of the inner shell adjacent the front wall of the inner shell and having
55 article engaging portions extending toward the back plate, said cradle being pivoted at a point intermediate said article engaging portions, a post extending from the cradle through an aperture in the front wall of the inner shell into the relatively narrow space between the inner and outer shells, and means for so directing a descending coin as to rock the post and the cradle and to thereby receive an article from the magazine on to the cradle, said cradle being adapted to thereafter rock in the opposite direction and arrest the next descending article.

19. In a vending machine, a back plate, an inner shell coöperating therewith and defining a relatively flat article magazine, an article retaining and delivering cradle therein, comprising a piece of sheet metal struck up into crescent shape and having
75 pivot portions journaled in the side walls of the inner shell and at a point adjacent the front wall of the inner shell, and a projection therefrom extending through an aperture in the front wall of the inner shell,
80 and coin actuated means for rocking the cradle to receive an article thereon from the article magazine.

In witness whereof, I have hereunto set my hand this 1st day of November, 1915. 90
ROGER W. PERRIN.
